REFRIGERATING APPARATUS

Earnest J. Dillman, Detroit, Mich., assignor to
Detroit Lubricator Company, Detroit, Mich., a
corporation of Michigan

Original application June 17, 1930, Serial No.
461,669. Divided and this application July 30,
1934, Serial No. 737,526

22 Claims. (Cl. 62—5)

My invention relates to new and useful improvements in control devices, and more particularly to a device or apparatus having one or more means for automatically regulating or controlling one or more control devices in response to predetermined conditions or changes of conditions, such that certain mechanism or apparatus in connection with which the control device or devices is or are employed, will be controlled or regulated in a desired manner. While it is evident that the control apparatus of my invention is capable of use with or embodiment in a multiplicity of different systems or apparatus, I have chosen, for the purpose of these specifications, to disclose the same in cooperable relation with a refrigerating system or apparatus, preferably of the absorption type, the cycle of operation of which is well known in the art.

The invention consists in the improved construction and combination of parts and their aggroupment in operative relation, all to be more fully described hereinafter, and the novelty of which will be particularly pointed out and distinctly claimed.

In the accompanying drawings, to be taken as a part of these specifications, I have fully and clearly illustrated a preferred embodiment of my invention, in which drawings:

Figure 1 is a view in front elevation, partly diagrammatic, having certain parts broken away, and being partly in vertical section, of an apparatus embodying my invention;

Fig. 2 is an enlarged detail view, partly in vertical central section, of my control device shown in Fig. 1, but with the cover or closure member thereof removed;

Fig. 3 is an enlarged detail view in vertical section, of part of the control device, and

Fig. 4 is an enlarged detail view of a part of an element of the control device.

Referring to the drawings by characters of reference, there are in the system or apparatus (Fig. 1) a generator-absorber A, a condenser B, a refrigerant reservoir C, a flow control means D, an evaporator E, and my control device or apparatus F, all connected in operative relation, as will be described.

The generator-absorber A comprises a housing or casing member 1 with insulated side walls, 50 and having a top and a bottom wall 2, 3, respectively. In the top and bottom walls are preferably two outlet and two inlet openings 4, 4^a and 5, 5^a, respectively, which are preferably at the sides of the member 1 and extend completely from front to rear thereof. The interior

of member 1 is preferably divided into vertical flow passages 6, 7 and 8 by partitions, or the like, 9, 10 which terminate short of the top and bottom walls, and which are in the respective planes of the substantially aligned openings 4, 5 5 and 4^a, 5^a. Control means 11, such as dampers, flap valves, or the like, are provided for each of the openings 4, 4^a and 5, 5^a, which, when in position, cooperate with the partitions to close the passages 6 and 8, and which when in closed 10 position provide for circulation from passage 7 to passages 6 and 8 and then back to passage 7, as is apparent from Fig. 1. The means 11 are preferably carried by rotatable shafts journaled in the member 1 and having any suitable inter- 15 connecting linkage 12, whereby the means 11 are movable in unison to open and to closed positions. Within the passage 7 is a sealed container means 13, which preferably comprises a plurality of vertically positioned steel tubes having headers, or the like, 14 at top and bottom, the top header alone being shown, and which contains or is adapted to contain an absorbent or adsorbent medium, such, for example, as silica gel, or the like, designated 15. Sealed to and extending from the top header 14 is a conduit member 16 serving as a common delivery and return duct. In the bottom wall 3 is an aperture 17 positioned beneath means 13 for admission to the interior of member 1 of a heating means 18, preferably a gas or other fluid fuel main burner means supplied from any suitable source by a conduit member 19 having therein a flow control device or valve means 20, to be further described. The burner means 18 is preferably provided with a pilot burner 21 fed through a valve controlled conduit member 22 connected to member 19 on the supply side of means 20. Supported by the top wall 2 is a drive means 21^a, preferably an electric motor, having its drive shaft 23 vertically positioned and extending at its lower end through the wall 2 into passage 7. On the top and bottom ends of the shaft 23 are secured fan means 24, 25, respectively, for creating a forced gas flow. A vent pipe 26 opening from passage 45 8 to atmosphere is preferably provided.

Supported on top of the casing member 1 is the condenser B, preferably of the air cooled type, which is positioned directly over the fan means 24 and which is mounted on a housing 27 for the 50 fan means 24. The housing 27 has inlet openings 27^a at front and rear below the means 24, so that cooling air or gases will be drawn into the housing by the means 24 and forced up through and over the condenser B. Extending from the 55

top inlet end of the condenser B is a conduit member 28 which connects into a valve casing 29 and through a check valve 30 therein to the conduit member 16, the valve 30 opening toward 5 the condenser B.

From the lower outlet end of the condenser B extends a conduit member 31 in which is a check valve 31^a closing toward the condenser B and which leads to the flow control means D. Positioned in the conduit member 31 is the refrigerant medium receiver C. The means D is preferably a float valve such, for example, as that disclosed and claimed in the patent to Lewis W. Eggleston, No. 1,832,693, granted November 17, 15 1931.

From the means D leads a conduit member 32 to the evaporator E, from which passes a conduit member 33 to the valve casing 29 and through a check valve 34 therein to the conduit member 20 16, the valve 34 opening toward the member 16. The refrigerant medium which passes through conduit members 16, 28 and 33 is substantially in the vapor state, and these members are therefore 25 preferably of larger diameter bore than members 31 and 32 which convey the medium in liquid state.

Mounted on brackets, or the like, on the front wall of member 1, is the control device F, which 30 preferably has a substantially rectangular supporting framework 34^a having top and bottom frame members 35, 36 and end frame members 37, 38. Rigidly secured in an aperture in the bottom member 36 and depending therefrom, is the valve means 20 having a port 39 with which 35 operates a reciprocable valve member 40 carried by a stem 41 having a sliding fit in and extending up through a guide aperture in the valve bonnet 42. Between and secured to the top and bottom members 35, 36 is a substantially vertical supporting frame member 43 having a horizontal 40 guide aperture 44 therethrough adjacent its midportion. Extending through the aperture 44 is a reciprocable thrust member or plunger 45 carrying thereon a slidable sleeve member 46, preferably 45 of brass, having guided bearing in the aperture 44. Intermediate its ends the plunger 45 is screw threaded and adjustably carries an operating nut or trip member 47 for a purpose to be described, and which also serves to limit movement 50 of said sleeve member 46 in one direction. Movement of member 46 in the opposite direction is limited by a collar or stop member 48 rigid with plunger 45, and preferably seated in a circumferential groove therein. Movable relative to 55 member 46 and carried thereby is an abutment or operating member 49, preferably an annulus of hardened tool steel having sharp, marginal edges on its inner circumference, as at 50, 51 (see Fig. 3). The member 49 is of slightly larger 60 internal diameter than the external diameter of member 46, so that when tilted from a plane substantially normal to the longitudinal axis of plunger 45, the edges 50, 51 of member 49 will bite into member 46 and cause member 49 to 65 move positively therewith. Normally acting on the member 49 is a resilient means 52 tending to slide member 49 along member 46 from left to right of Figs. 2 and 3 and toward frame member 38. The means 52 is preferably a leaf spring 70 member fixed, as at 53, to frame member 43 and bifurcated at its upper free end so as to pass to each side of member 46 and engage abutment member 49 at opposite points adjacent its horizontal diameter. Extending rigidly from frame 75 member 43 toward frame member 38 below and

substantially equidistant laterally from member 46, are supporting arm members 54 having a substantially horizontal bearing pin or rod member 55 extending rigidly therebetween. Pivotedly supported on pin 55 is a lever member or means 56 extending toward frame member 38 and having substantially parallel, horizontally spaced rigidly connected arm portions 57, 58 through which are aligned bearing apertures 59 receiving the pin 55. Connecting the portions 10 57, 58 is a transverse or base portion 60 from the top and bottom edges of which members 61, 62, respectively, extend toward frame member 38 in substantially parallel relation. The members 61, 62 extend through an aperture 63 in a substantially 15 vertical bracket member 64. The bottom edge 65 of aperture 63 cooperates with member 62 to limit or stop downward movement of means 56. The arm portions 57, 58 are joined above pin 5 by a pin or rod 66 which is positioned just under sleeve member 46 and for engagement by the abutment member 49 upon its movement from left to right of Figs. 2 and 3. At its top the bracket member 64 has a lateral extension or arm 67 which overlies the member 61 and through 20 which is adjustably threaded a stop screw 68 co-operable with member 61 for regulating and limiting the permissible upward movement of means 56. Extending in prolongation of and substantially horizontally from the top of arm portion 57, 30 is an operating arm or member 69 which passes through an aperture 70 in end frame member 38, and has pivotally secured on its free end, as at 71, an adjustable link or rod 72 which connects to the damper operating linkage 12, and preferably to one of the inlet opening damper shafts. Also fulcrumed on pin 55 between arm portions 35 57, 58, is a lever or lifting member 73, preferably comprising substantially parallel rigidly connected arms 74 of substantially triangular form, having their bases preferably substantially vertical and their apices apertured to receive the pin or shaft 55. The upper ends of arms 74 extend on opposite sides of plunger 45 and in proximity thereto, and terminate in fingers or trip members 75 substantially at or above the contact points between leaf spring 52 and member 49 for engagement with the abutment member 49 to disengage the same from biting engagement with sleeve member 46. The member 73 also acts upon 40 upward counterclockwise movement about pin 55 to engage pin 66 subsequent to engagement of fingers 75 and members 49 to left or rotate lever means 56 counterclockwise of Fig. 2. In opposing relation to the stop member 62 which extends beyond member 61, is a substantially horizontal lever member 76 which extends over the valve stem 41 and freely through an aperture 77 in frame member 38. The member 76 is provided with knife-edge fulcrum portions 78 which engage the inside face of member 38. Interconnecting and pivoted to the member 76 and stem 41 is a link, or the like, 79 which serves to transmit motion from member 76 to the valve member 40. The members 62 and 76 terminate in conical points 80, 81, respectively, which seat in bearing recesses in spring follower members 82, 83 between which and held under compression thereby is a resilient means 84, preferably a coil spring. The screw 68 is preferably so adjusted and the 50 length of link 79 is such that when the lever means 56 is in upper position and valve 20 is closed, as in Fig. 2, the point 80 will be very slightly above the line of points 55 and 81, that is, the toggle joint will be broken upward slightly. 55 60 70 75

Rigidly supported on the lever member 16 and extending at an inclination upward therefrom, is an abutment arm 85. Secured to and depending from the top frame member 35 are supporting arms 86 between which is fulcrumed, on a bearing pin 87, a lever member 88, which extends over the abutment arm 85 and from which depends a rod member 89 cooperable with arm 85 to depress the same. Positioned between members 35 and 88 is a coil spring, or the like, 90 under compression and normally tending to force member 89 into engagement with arm 85 to close valve 20. The spring 90 is opposed and normally held inactive by pilot burner responsive means 91 which has a bulb element 92, see Fig. 1, charged with a heat responsive medium and positioned to be heated by the flame of pilot burner 21. Extending from element 92 is a conduit 93 which connects into casing 94 secured to the top frame member 35 above lever member 88 and on the opposite side of its fulcrum from spring 90. The casing 94 is sealed by resilient means (not shown), such as a metal bellows, which carries a plunger 95 engaging the lever member 88 on the opposite side of its fulcrum from spring 90 so that the presence of a proper pilot burner flame will maintain member 89 in the position of Fig. 2. Pivoted secured between the lifting member arms 14 at their lower ends 30 and on a pin 96, is a depending plunger 97 extending through a spring adjustment nut 98 and an aperture in the bottom frame member 36. Fixed to the underside of member 36 is the power element 99 of a means responsive to variation in a fluid characteristic, preferably temperature, and which comprises a casing 100 sealed by resilient means 101, preferably a metal bellows, having fixed thereto a plunger 102 operatively connected to plunger 97. Within the bellows 101 around plunger 102, is a coil spring, or the like, 103 under compression and which seats against the bellows head and the nut 98, and by which the response of the responsive means may be regulated. Leading from the chamber 104 within the casing 100, is a conduit 105 having sealed to its free end a bulb element, or the like, 105^a charged with a suitable expansive medium and positioned within the generator-absorber passage 7, so that upon occurrence of a predetermined temperature or variation in temperature of the heating gases in passage 7, the element 99 will be actuated to force the plunger 97 and lifting member 13 upward. Secured to the end frame member 37 is a power element 106 having a casing 107 within which is a plunger 108 in substantial alinement with plunger 45 and operatively connected thereto. The plunger 108 is carried by resilient means 109, preferably a metal bellows, which seals the casing 107. Within the bellows 109 is a coil spring 110 under compression and surrounding plunger 108 and seating against the head of bellows 109. At its other end the spring 110 abuts an externally threaded apertured nut 111 which is adjustably screwed into the frame member 37. The element 106 comprises part of a means responsive to variation in a fluid characteristic, preferably pressure, and has a conduit 112 connecting the chamber 113 within the casing 107 to the refrigerant medium return conduit member 33. Positioned on the top of the top frame member 35 is an electric switch means 114, preferably of the enclosed contact tilting mercury tube type having terminals 115, 116 extending through the wall of the tube 117 and from which lead conductors 118, 119 to the

fan motor 21. The switch tube 117 is held in a clip member 120 which is pivotally supported on a pin 121 carried by a bracket 122 to permit rocking or tilting movement of the tube to flow the mercury to and from the contacts. The tube 117 is counterweighted by a member 123 which tends to maintain the motor circuit closed. Projecting from the clip member 120 is a lug 124 in the path of movement of one end of a lever arm 125 which passes downward through an aperture 126 in the top frame member 35, and which is fulcrumed intermediate its ends on a bracket supported pin 127. The other end of arm 125 extends to the left of and into cooperable relation with the plunger carried trip member 41, so that movement of plunger 45 from right to left of Figs. 2 and 3 acts to break the circuit of motor 21^a within tube 117.

The operation of my control device or apparatus as embodied, for example, in a refrigerating system of the absorption type, will now be described, it being understood that the control device is capable of embodiment in other systems and for controlling other means. In the drawings, the positions of the various elements of the system are such as occur on the completion of a heating cycle, and after the generator-absorber A has been cooled somewhat. Continuing from this point in a cycle of operation, the functioning of the system under command of my control device is as follows: The heat given off from the container means in passage 7 will cause a natural upward flow of cooling gases or air in passage 7, which cooling air enters at inlet openings 5, 5^a and leaves via outlet openings 4, 4^a, the damper means 11 being in the positions shown and the main burner 18 having been extinguished. The temperature at the evaporator E will be above the predetermined low limit for which the power element 106 is set, and therefore pressure of the vaporized refrigerant medium, such, for example, as sulphur dioxide, in the conduit member 33 acting on the resilient chamber sealing means 109 will have moved the interconnected plungers 108 and 45 to the right of Figs. 2 and 3 at the start 45 of the now completed heating cycle. The plunger 45 carries the nut or trip member 41 which on movement of plunger 45 to the right of Figs. 2 and 3 will have released switch tube 117, permitting the weight member 123 to tilt the same clockwise 50 on its pivot 121 to energize the fan motor 21^a. The fan 25 driven by motor 21^a will create a forced upward draft through passage 7, increasing the rate of cooling of the generator-absorber and container means 13. The cooling of the means 13 will reduce the pressure therein, causing the liquefied refrigerant medium in the evaporator E to vaporize and pass back through conduit member 33, the check valve 34 and conduit member 16 to the container means 13, for absorption or adsorption by the medium 15 therein. As the evaporator cools, due to the vaporization of the refrigerant medium, the pressure characteristic of the vaporized refrigerant medium or fluid in conduit 33 will decrease, thus decreasing there- 65 with the pressure in power element chamber 113, which under the inherent resilience of sealing means 109 and spring 110 will move trip member 41 to the left of Figs. 2 and 3. Upon attainment of substantially the desired low temperature at 70 the evaporator, the trip member 41 acting through lever 125 will have tilted the tube 117 counterclockwise of Fig. 2, breaking the circuit to the fan motor 21^a, and thus decreasing the rate of vaporization in the evaporator. The tube 117 75

will be tilted back and forth to make and break the motor circuit during the cooling cycle in response to variation within predetermined limits in the fluid characteristic transmitted to power element chamber 113, but due to the relative permitted movement between plunger 45 and its sleeve 46, the plunger member 45 will not actuate the lever means 56. When the absorbing or adsorbing power of the medium 15 in container means 13 has been substantially satisfied, the pressure in conduit member 33 will continue to increase beyond the pressure necessary to start motor means 21^a, and regardless of the increased flow by the fan 25 of cooling air which will now continue until the evaporator is again cooled down as above described. The limiting stop or nut 47 will take up the play between plunger 45 and sleeve 46, causing the abutment or ring member 49 to engage the cross pin or member 66. Continuation of the movement of plungers 108 and 45 to the right of Figs. 2 and 3 will cause the ring member 49, backed up by leaf spring 52, to tilt from the normal to plunger 45 into biting or gripping relation to sleeve 46, as in Figs. 2 and 3. When the ring member 49 has been tilted and tightly grips the sleeve 46, then movement of plunger 45 to the right will act through this established positive engagement with lever means 56 to rotate or move the same clockwise about its pivot pin 55, which will initiate the heating period. As above noted, the break point 80 between means 56 and spring 84 is very slightly above and over-center, and therefore the movement of plunger 45 necessary to carry point 80 through center is very slight. As the point 80 crosses center, the compressed spring 84 will act with an increasing component to force the lever means 56 and arm 69 downward and clockwise about pin 55 into engagement with stop 65. The downward movement of point 80 carries it across the line of points 81, 78, so that the spring 84 will react with an upward component on the lever 76, swinging the same clockwise of Fig. 2 about its knife edge fulcrum 78. The upward movement of lever 76 is transmitted through link 79 to valve stem 41 to open valve 20 and permit fuel to flow to the main burner means 18. The fuel supplied to means 18 will be ignited by the pilot burner 21. Should it happen that the pilot burner flame is insufficient to heat the bulb element 92, then the spring 90 will have acted through arm 85 to hold the valve member 40 on its port 39 against the lifting component of force of spring 84, and thus prevent flow of fuel to the burner means 18. It is of course understood that the bulb element 92 and responsive means 91 comprise a safety device, which on failure, or substantial failure, of the pilot burner flame will act to close the valve 20 or to extinguish the main burner means 18 and stop operation of the system. The downward movement of lever arm 69, as above described, acts through the rod 72 and linkage 12 to operate the damper means 11 to close the inlet openings 5, 5^a and the outlet openings 4, 4^a. The gases within casing member 1 which are heated by means 18, will rise over the container means 13 and be forced by the running fan 25 to travel down the passages 6 and 8 for continuous recirculation and heating. During the heating period, refrigerant medium in the vapor state will be driven off from the absorbent or adsorbent medium within container means 13, and will pass through top header 14 to conduit member 16. The check valve 34 will direct the flow through conduit member 28, past check valve

30, to the condenser B. The motor means 21^a which is constantly energized during the heating period, will also drive fan 24, which will force cooling air upward over the condenser B to cool and liquefy the refrigerant medium supplied thereto. The liquefied medium will pass through the valve controlled conduit member 31 to the evaporator E, any surplus being stored in the receiver C until permitted by the flow control means D to enter the evaporator E via the conduit member 32. When the recirculating gases within the housing member 1 have been heated to a predetermined degree, say, about 400° F., substantially all of the refrigerant medium will have been driven off from the absorbent or adsorbent medium 15 in container means 13 and have passed to the condenser B. Upon the temperature within the generator-absorber reaching the desired degree, the fluid within the bulb element 105^a of the responsive means will have acted upon the resilient sealing means 101 to force plungers 102 and 97 and the lifting member 73 upward. As the lifting member 73 moves upward, the upper inclined edges of the arms 74 will engage the underside of cross-pin 66 and lift lever means 56 upward, or counterclockwise, about its fulcrum 55 against the force of spring 84, until point 80 crosses center, when spring 80 will snap the lever means 56 up against stop screw 68. During the latter part of the upward movement of lifting member 73, the fingers 75 thereof will engage the ring member 49 and turn it back to substantially vertical position as it fulcrums on the leaf spring 52, and will then slide or move it toward the left of Figs. 2 and 3 against the force of spring 52 and along sleeve 46, so that it will be out of the way of the cross-pin 66 and not stop or hinder upward movement of lever means 56. The valve 20 will be snapped closed by the force of spring 84 as point 80 passes through the extended line of points 81, 78, which operation starts the cooling period in the cycle. The damper arm 69, which is moved upward with lever means 56, acts through rod 72 and linkage 12 to operate the damper means 11 to open inlet openings 5, 5^a and outlet openings 4, 4^a, closing passages 6 and 8. The fan 25 will continue in operation, cooling the container means 13 and the atmosphere in passage 7. As the temperature in passage 7 decreases, the fluid in bulb element 105^a will contract, permitting spring 103 in the power element 99 to move connected plungers 102 and 97 and lifting means 73 downward to the position shown in Fig. 2, thus completing a cycle of operation of the system and of the control device.

It may be noted that the spring 52 will return the abutment member 49 to the right along sleeve 46 to its operative location as the lifting means 73 and fingers 75 are retracted. It may also be noted that the cooperating sleeve 46 and annulus 49 permit a very sensitive operation as the annulus is operable to grip tightly the sleeve 46 anywhere within the length of the sleeve.

The above described cycle is descriptive of the normal operation of the control device and system. However, upon initial operation or starting of the system with the evaporator substantially at room temperature, there may be several cycles during which the motor means 21^a will operate continuously, because the temperature of the evaporator E may not drop sufficiently in the first few cycles to permit spring 110 to retract plunger 45 far enough to the left to tilt tube 117 and break the motor circuit.

Although my control device and apparatus has been described as functioning in connection with a refrigerating apparatus employing silica gel as the absorbent or adsorbent medium and sulphur dioxide as the refrigerant medium, it will be apparent that the refrigerating apparatus may utilize ammonia as the refrigerant medium and water as the absorbing medium.

This application is a division of my copending application Serial No. 461,669 filed June 17, 1930.

What I claim and desire to secure by Letters Patent of the United States is:

1. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, and means responsive to a condition in said evaporator to actuate said control means to said other position.

2. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, means responsive to a condition in said evaporator to actuate said control means to said other position, and means to create a forced flow of the cooling gases.

3. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, means responsive to a condition in said evaporator to actuate said control means to said other position, and means to create a forced recirculation of the heating gases.

4. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, means responsive to a condition in said evaporator to actuate said control means to said other position, and means to create a forced flow of cooling gases and a forced recirculation of heating gases.

5. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of

heating gases over said generator-absorber, means responsive to a condition in said generator-absorber to actuate said control means to said one position and to stop said heating means, and means responsive to a condition in said evaporator to actuate said control means to said other position.

6. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, and means responsive to a condition in said evaporator to actuate said control means to said other position and to start said heating means.

7. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, means responsive to a condition in said evaporator to actuate said control means to said other position, and means to create a forced flow of the cooling gases, said first-named responsive means controlling said last-named means whereby to regulate the temperature about said evaporator.

8. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means to cool said condenser, means responsive to a condition in said generator-absorber to actuate said control means to said one position, and means responsive to a condition in said evaporator to actuate said control means to said other position, said first-named responsive means controlling said condenser cooling means.

9. A refrigerating apparatus, comprising a generator-absorber, a condenser and an evaporator connected in operative relation, burner means to heat said generator-absorber, control means operative in one position to establish flow of cooling gases over said generator-absorber and operative in another position to establish recirculation of heating gases over said generator-absorber, a pilot burner for said burner means, means responsive to substantial failure of said pilot burner to stop said heating means, means responsive to a condition in said generator-absorber to actuate said control means to said one position, and means responsive to a condition in said evaporator to actuate said control means to said other position.

10. A refrigerating apparatus, comprising a generator-absorber, a condenser and an evaporator connected in operative relation, means to heat said generator-absorber, control means operative in one position to establish flow of cooling gases over said generator-absorber and op-

- erative in another position to establish recirculation of heating gases over said generator-absorber, means responsive to a predetermined increase of temperature in said generator-absorber 5 to actuate said control means to said one position, and means responsive to a condition in said evaporator to actuate said control means to said other position.
11. A refrigerating apparatus, comprising a generator-absorber, a condenser and an evaporator connected in operative relation, means to heat said generator-absorber, control means operative in one position to establish flow of cooling gases over said generator-absorber and operative in another position to establish recirculation of heating gases over said generator-absorber, means responsive to a condition in said generator-absorber to actuate said control means to said one position, and means responsive 15 to a predetermined rise of pressure in said evaporator to actuate said control means to said other position.
12. A refrigerating apparatus, comprising a housing member having a longitudinally extending partition therein forming flow passages, sealed container means within one of the passages of said member and containing an adsorbent or absorbent medium and a refrigerant medium, said member having an inlet and an outlet, damper means for said inlet and said outlet and operable in one position to close said inlet and said outlet for circulation in said member and around said partition and operable in another position to open said inlet and said outlet 25 for flow through said one passage to and from said housing, motor driven fan means in said one passage, an evaporator, a conduit connecting said container means and said evaporator and having flow control means, a condenser in said conduit between said flow means and container means, a conduit connecting said evaporator and said first-named conduit between said container means and said condenser and having a check valve therein opening to said first-named conduit, a thermostat responsive to temperature in said one passage, burner means having a pilot burner and positioned in said one passage to heat said container means, valve means for said burner means, said thermostat being operable 30 upon predetermined temperature to close said valve means and to move said damper means to said other position, and means responsive to pressure in said second-named conduit, said responsive means being operable at a predetermined low pressure to stop said motor means and at a predetermined high pressure to start said motor means, and being operable upon a predetermined higher pressure to open said valve means and to move said damper means to said one position.
13. In a refrigerating system, the combination with a main refrigerant circuit containing an aqueous solution of ammonia, and including a generator, a condenser, and an evaporator; of an electric fan adapted to cool said condenser; a switch adapted to control said fan; and thermostatically operative means adapted to operate said switch to start and stop said fan, in accordance with the temperature of the ammonia in said system.
14. In a refrigerating system, the combination with a refrigerant circuit containing a refrigerant medium, and including a generator, a condenser, and an evaporator, of an electric fan adapted to cool said condenser, a switch adapted 70 to control said fan, and means to operate said switch to start and stop said fan in accordance with a characteristic of the refrigerant medium.
15. A refrigerating apparatus, comprising a generator-absorber, a condenser and an evaporator connected in operative relation and containing a refrigerant medium, means to heat said generator-absorber, means to control said heating means, a fan operable to cool said condenser, drive means for said fan, means to control said drive means, and means responsive to a characteristic of said medium for actuating said first-named and said second-named control means. 5
16. A refrigerating apparatus, comprising a generator-absorber, a condenser and an evaporator connected in operative relation, means to heat said generator-absorber, damper means movable into one position to establish flow of cooling gases over said generator-absorber and movable into another position to establish recirculation of heating gases over said generator-absorber, control means operable on movement in one direction to move said damper means to said one position and to stop said heating means and operable on movement in another direction 10 to move said damper means to said other position and to start said heating means, means responsive to a condition in said evaporator, means operatively connecting said responsive means and said control means whereby movement of said responsive means will act to move said control means in said other direction, means responsive to a condition in said generator-absorber, and means to transmit movement from said last-named responsive means to said control means 20 to move said control means in said one direction. 25
17. A refrigerating apparatus, comprising a generator-absorber, a condenser and an evaporator connected in operative relation, means to heat said generator-absorber, damper means movable into one position to establish flow of cooling gases over said generator-absorber and movable into another position to establish recirculation of heating gases over said generator-absorber, control means operable on movement 30 in one direction to move said damper means to said one position and to stop said heating means and operable on movement in another direction to move said damper means to said other position and to start said heating means, means responsive to a condition in said evaporator, means operatively connecting said responsive means and said control means whereby movement of said responsive means will act to move said control means in said other direction, means responsive to a condition in said generator-absorber, means to transmit movement from said last-named responsive means to said control means 35 to move said control means in said one direction. 40
18. A refrigerating apparatus, comprising a generator-absorber, a condenser and an evaporator connected in operative relation, means to heat said generator-absorber, damper means movable into one position to establish flow of cooling gases over said generator-absorber and movable into another position to establish recirculation of heating gases over said generator-absorber, control means operable on movement 45 in one direction to move said damper means to said one position and to stop said heating means and operable on movement in another direction to move said damper means to said other position and to start said heating means, means responsive to a condition in said evaporator, means operatively connecting said responsive means and said control means whereby movement of said responsive means will act to move said control means in said other direction, means responsive to a condition in said generator-absorber, means to transmit movement from said last-named responsive means to said control means 50 to move said control means in said one direction, means to cool said condenser, and means controlled by said first-named responsive means to control said cooling means. 60
19. A refrigerating apparatus, comprising a generator-absorber, a condenser and an evaporator connected in operative relation, means to heat said generator-absorber, damper means movable into one position to establish flow of cooling gases over said generator-absorber and movable into another position to establish recirculation of heating gases over said generator-absorber, control means operable on movement 65 in one direction to move said damper means to said one position and to stop said heating means and operable on movement in another direction to move said damper means to said other position and to start said heating means, means responsive to a condition in said evaporator, means operatively connecting said responsive means and said control means whereby movement of said responsive means will act to move said control means in said other direction, means responsive to a condition in said generator-absorber, means to transmit movement from said last-named responsive means to said control means 70 to move said control means in said one direction, means to cool said condenser, and means controlled by said first-named responsive means to control said cooling means. 75

and to start said heating means, means responsive to a condition in said evaporator, means operatively connecting said responsive means and said control means whereby movement of said responsive means will act to move said control means in said one direction, means responsive to a condition in said generator-absorber, means to transmit movement from said last-named responsive means to said control means to move said control means in said one direction, a fan operable to cause flow of cooling gases over said condenser, and means controlled by said first-named responsive means to control said fan.

19. A refrigerating apparatus, comprising a generator-absorber, a condenser and an evaporator connected in operative relation, means to heat said generator-absorber, damper means movable into one position to establish flow of cooling gases over said generator-absorber and movable into another position to establish recirculation of heating gases over said generator-absorber, control means operable on movement in one direction to move said damper means to said one position and to stop said heating means and operable on movement in another direction to move said damper means to said other position and to start said heating means, means responsive to a condition in said evaporator, a pair of members cooperable with said responsive means and said control means, one of said members having means movable thereon and normally establishing cooperable relation between said members whereby said responsive means can move said control means in said other direction, means responsive to a condition in said generator-absorber, and means to transmit movement from said last-named responsive means to said control means and to move said establishing means out of cooperable relation between said members, whereby said second-named responsive means is operable to move said control means in said one direction.

20. A refrigerating apparatus, comprising a generator-absorber, a condenser and an evaporator connected in operative relation, a fluid fuel burner to heat said generator-absorber, damper means movable into one position to establish flow of cooling gases over said generator-absorber and movable into another position to establish recirculation of burner heating gases over said generator-absorber, a valve controlling flow of fuel to said burner, control means operable on movement in one direction to move said damper means to said one position and to close said valve and operable on movement in another direction to move said damper means to said other position and to open said valve, means responsive to a condition in said evaporator, means operatively connecting said responsive means and said control means whereby movement of said responsive means will act to move said control means in said other direction, means responsive to a condition in said generator-absorber, means to transmit movement from said last-named responsive means to said control means to move said control means in said one direction, a pilot burner for said fluid fuel burner, means responsive to a condition of said pilot burner, and means operable by said last-named means to close said valve irrespective of said first-named control means.

21. A refrigerating apparatus, comprising a generator-absorber, a condenser and an evaporator connected in operative relation, means to heat said generator-absorber, means to control said heating means, damper means movable into one position to establish flow of cooling gases over said generator-absorber and movable into another position to establish recirculation of heating gases over said generator-absorber, control means operable on movement in one direction to move said damper means to said one position and operable on movement in another direction to move said damper means to said other position, means responsive to a condition in said evaporator, means operatively connecting said responsive means and said second-named control means whereby movement of said responsive means will act to move said second-named control means in said other direction, means responsive to a condition in said generator-absorber, and means to transmit movement from said last-named responsive means to said second-named control means to move said second-named control means in said one direction.

22. A refrigerating apparatus, comprising a generator-absorber, a condenser and an evaporator connected in operative relation, means to heat said generator-absorber, means to control said heating means, damper means movable into one position to establish flow of cooling gases over said generator-absorber and movable into another position to establish recirculation of heating gases over said generator-absorber, control means operable on movement in one direction to move said damper means to said one position and operable on movement in another direction to move said damper means to said other position, means responsive to a condition in said evaporator, means operatively connecting said responsive means and said second-named control means whereby movement of said responsive means will act to move said second-named control means in said other direction, means responsive to a condition in said generator-absorber, means to transmit movement from said last-named responsive means to said second-named control means to move said second-named control means in said one direction, means to cool said condenser, and means controlled by said first-named responsive means to control said cooling means.

EARNEST J. DILMAN

CERTIFICATE OF CORRECTION.

Patent No. 2,072,423.

March 2, 1

EARNEST J. DILLMAN.

It is hereby certified that error appears in the printed specification of the above numbered patent requiring correction as follows: Page 1, first column, line 43, for "absober" read absorber; and second column, line 8, after the word "in" insert open; page 2, second column, line 20 for the reference numeral "5" read 55; line 53, for "left" read lift; page 5, first column, line 20, claim 1, for "generator, absorber" read generator-absorber; and that the said Letters Patent should be read with these corrections therein that the same may conform to the record of the case in the Patent Office.

Signed and sealed this 6th day of April, A. D. 1937.
